UNITED STATES PATENT OFFICE

157,510

POWER UNIT FOR A FOOD MIXER OR THE LIKE

Anthony Naiden, Southwick, Mass., assignor to
Westinghouse Electric Corporation, East Pitts-
burgh, Pa., a corporation of Pennsylvania

Application January 10, 1948, Serial No. 143,644

Term of patent 14 years

(Cl. D44—1)

To all whom it may concern:

Be it known that I, Anthony Naiden, a citizen of the United States, residing at Southwick, in the county of Hampden and State of Massachusetts, have invented a new, original, and ornamental Design for a Power Unit for a Food Mixer or the like, of which the following is a specification, reference being had to the accompanying drawings, forming a part thereof.

Fig. 1 is a front perspective view of a power unit for a food mixer or the like, showing my new design;

Fig. 2 is a rear perspective view;

Fig. 3 is a top plan view; and

Figs. 4, 5 and 6 are side, rear and front elevational views, respectively.

The characteristic features of the design reside in the portions shown in full lines on the drawings.

I claim:

The ornamental design for a power unit for a food mixer or the like, substantially as shown and described.

ANTHONY NAIDEN.
